Patented Dec. 9, 1975

237,941

GOLF CART UMBRELLA MOUNT

William F. Dotter, 49 Spruce St.,
Smithtown, N.Y. 11787

Filed May 23, 1974, Ser. No. 472,622

Term of patent 14 years

Int. Cl. D8—08

U.S. Cl. D8—235

FIG. 2

FIG. 1

FIG. 1 is a perspective view of my golf cart umbrella mount; and

FIG. 2 is an enlarged perspective view taken from the other side of FIG. 1.

The broken lines are for illustrative purposes only.

I claim:

The ornamental design for a golf cart umbrella mount, as shown and described.
